METHOD OF AND MACHINE FOR PREPARING
MOLDING AND PACKING SAND AND LIKE
MATERIAL

Heinrich Wagner, Laasphe-on-the-Lahn, Germany, assignor to Müller und Wagner, Modell u. Maschinenbau, Wallau near Biedenkopf, Lahn, Germany

Application July 3, 1937, Serial No. 152,548
In Germany September 5, 1938

6 Claims. (Cl. 209—214)

It is known to prepare the molding sand for use in foundries by projecting the initial material to form a stream in a projecting machine in order to separate the wanted from the unwanted ingredients. Particles of iron in the sand are, however, not separated out by this means, so that a separate iron separator, usually an electromagnet, has been used in order to remove the iron from the molding sand either before or after it has been thrown as described. The use of the iron separator, however, has the disadvantage that the possible output of the projecting or conditioning machine is limited since the sand must pass a good deal more slowly through the separator than through the projecting machine. In order, therefore, to obtain the same output a number of separators must be used with one projecting machine.

This disadvantage is obviated by the present invention, whereby the magnetic separation of the particles of iron is effected in the stream of the projected sand itself. The sand is already loosened or spread out by the projecting process by the time it arrives at the magnet, so that even the smallest particles of iron are free from the sand particles and are, therefore, at once attracted by the magnet. Furthermore, in this process the output of the projecting machine is not reduced. One can give the sand stream a high velocity and yet be assured that the iron particles are substantially completely removed from it by the magnet.

The magnet is preferably so arranged that the projected sand streams are immediately underneath it. The iron particles are heavier than the sand and are, therefore, uppermost in the sand stream. If necessary separate iron fingers or lamellae can be mounted on the magnet which project into the sand stream and remove even the somewhat more deeply suspended iron particles.

The process is carried out with periodical de-energisation of the magnet, when it is covered with iron particles, and this can be done by switching off the energising current or stopping the current generator which supplies the energising windings of the magnet. At the time of such de-energisation the feeding of sand to the projecting apparatus is also interrupted. The iron particles held by the magnet then fall, preferably into a container. The periodical de-energisation of the magnet can be effected by hand or automatically by any appropriate switching device.

An example of a machine for carrying out the

invention is illustrated by the accompanying drawing, in which:

Fig. 1 is a part longitudinal section;
Fig. 2 is a plan partly in section, and
Figs. 3 and 4 show alternative forms of the electromagnet.

The projecting apparatus, which consists in known manner of two drums 3 and 4 over which runs an endless band 5 of rubber or other suitable material, is mounted on a carriage 2 supported by wheels 1. A large number of projection members 6 is fixed to the band 5. The machine is driven by an electric motor 7 through a belt 8 and the drum 4. At the same time the motor also drives through a belt 9 a generator 10 which generates the energising current for the electromagnet 11. The latter may have the form shown in Fig. 3 or Fig. 4, and is arranged so that it lies over the sand stream projected by the belt 5. The underneath pole of the magnet may or may not be provided as shown in Fig. 4 with separate projecting plates 12 arranged as fingers or lamellae which project downwards into the projected sand stream. These plates when used are preferably somewhat sharpened on their front edges so that the sand can flow past them with as little hindrance as possible.

The projecting band 5 forms the floor of a container 13 into which the sand to be prepared is fed either by hand or through a mechanical feeding device. Behind the magnet 11 in the path of the sand there is provided, in known manner, a hood 14 which can be adjusted to deflect the sand stream downwards when it is not desired to project it far.

Under the electromagnet 11 is a container 15 into which the separated iron falls when the magnet is de-energised. The iron may be removed from this container through a door or flap into a larger intermediate container.

The machine operates as follows. The sand to be separated is loaded into the container 13 and moves with the band 5 and the members 6, these members moving at high velocity in the direction of the arrow. The sand stream 16 then flows under the electromagnet 11 and is projected a greater or less distance according to the adjustment of the hood 14. As they pass the electromagnet 11, which is excited by the generator 10, the particles of iron floating in the separated sand stream are attracted and held by the magnet. This action can be considerably increased by the lamellae shown in Fig. 4. As soon as a number of iron particles 17 have collected on the magnet the generator 18

10 is stopped by a suitable switching device, or the current to the magnet otherwise interrupted, so that electromagnet 11 is de-energised and the particles of iron thereon fall into the container 15. While the magnet is de-energised it is necessary to interrupt the loading of the sand into the container 13. When the generator current is again switched on the feeding of the sand can be re-commenced.

10 In certain circumstances the periodical interruption of the energising current can be effected automatically by a suitable switching device. If the energising current be permanently interrupted the machine can be used as a projecting 15 machine operating in known manner for sand or other material free from iron particles.

The electromagnet can be located otherwise than as shown; it is essential only that the pole or fingers should reach to the sand stream.

20 While the projecting machine shown is provided with a projecting band, a machine can obviously be used having one or more projecting wheels or other projecting means instead of a belt.

25 The process and the machine can also be used for separating the iron constituents from non-magnetic metal shavings or like material.

Having now particularly described and ascertained the nature of my said invention and in 30 what manner the same is to be performed, I declare that what I claim is:

1. The method of preparing sand for foundries and the like consisting of thoroughly dispersing and drying the raw sand by projecting it into 35 the atmosphere in a free, unconfined stream in an arc having an upward inclination to the horizontal said arc being free of any confining surfaces, and magnetically detaining the iron particles in the trajectory of the raw sand, the sand 40 particles being affected only by gravity.

2. The method of preparing sand for foundries and the like consisting of thoroughly dispersing and drying the sand by projecting it into the atmosphere in a free, unconfined stream in an 45 arc having an upward inclination to the horizontal said arc being free of any confining surfaces and magnetically detaining the iron parti-

cles adjacent the crown of said arc to permit the separated sand to fall freely during the period of descent.

3. The method of preparing sand for foundries and the like consisting in thoroughly dispersing and drying the sand by projecting it into the atmosphere in a free, unconfined stream in an arc having an upward inclination to the horizontal said arc being free of any confining surfaces and magnetically detaining the iron particles from said arc during the period of ascent to permit the separated sand to drop freely during the period of descent.

4. In a centrifuging apparatus for preparing raw sand and the like, means for projecting the sand into the atmosphere in a free, unconfined stream in an arc having an upward inclination to the horizontal said arc being free of any confining surfaces and an electro-magnet disposed above the trajectory of said projected sand particles and in the ascending portion thereof to detain the iron particles therein whereby the separated sand will fall freely in the descending portion of said arc.

5. In a centrifuging apparatus for preparing raw sand and the like, means for projecting the sand into the atmosphere in a free, unconfined stream in an arc having an upward inclination to the horizontal said arc being free of any confining surfaces and an electro-magnet disposed above the trajectory of said projected sand particles and adjacent the crown thereof whereby the separated sand will fall freely in the descending portion of said arc.

6. In a centrifuging apparatus for preparing raw sand and the like, means for projecting the sand into the atmosphere in a free, unconfined stream in an arc having an upward inclination to the horizontal said arc being free of any confining surfaces and an electro-magnet disposed above the trajectory of said projected sand particles and adjacent the crown thereof and having a plurality of fingers penetrating into the same, whereby the separated sand will fall freely in the descending portion of said arc.

HEINRICH WAGNER.
